(57) **CLAIM**

The ornamental design for “delineator bracket,” as shown.

DESCRIPTION

FIG. 1 is a perspective view of a first environmental view of the delineator bracket showing our new design;

FIG. 2 is a right side view thereof;

FIG. 3 is a top view thereof;

FIG. 4 is a bottom view thereof;

FIG. 5 is a rear view thereof;

FIG. 6 is a left side view thereof;

FIG. 7 is a front view thereof;

FIG. 8 is a perspective view of a second environmental view thereof;

FIG. 9 is a right side view thereof;

FIG. 10 is a top view thereof;

FIG. 11 is a bottom view thereof;

FIG. 12 is a rear view thereof;

FIG. 13 is a front view thereof;

FIG. 14 is a perspective view of a third environmental view thereof;

FIG. 15 is a right side view thereof;

FIG. 16 is a top view thereof;

FIG. 17 is a bottom view thereof;

FIG. 18 is a rear view thereof; and,

FIG. 19 is a front view thereof.

The broken line showing of a bracket element is for illustrative purposes only and forms no part of the claimed design.
